RELAY

Thomas Ross Welch, Los Angeles, Calif.

Application September 24, 1951, Serial No. 248,083

17 Claims. (Cl. 200—87)

1

This invention relates generally to circuit controlling devices and relates more particularly to improvements in relays.

It is an object of the present invention to provide a relay that is substantially free from the effects of vibrations.

It is another object to provide a device of this character having accurate adjusting means.

It is still another object of the invention to provide a device of this character wherein the adjustment means is effective in maintaining proper adjustments.

A further object of the invention is to provide a device of this character having high circuit controlling characteristics.

Still another object of the invention is to provide a device of this character having novel structural arrangements.

Another object of the invention is to provide a device of this character that is simple in construction and which has relatively few parts.

Still another object of the invention is to provide a device of this character that is sturdy and compact.

A further object of the invention is to provide a device of this character that is reliable in operation.

Other objects and advantages of the invention will appear in the following part of the specification.

Referring to the drawings, which are for illustrative purposes only:

Fig. 1 is the perspective view of a relay embodying the present invention;

Fig. 2 is a plan view thereof;

Fig. 3 is a sectional view taken on line 3—3 of Fig. 2;

Fig. 4 is a front end view of the device; and

Fig. 5 is a bottom view of the device as viewed from line 5—5 of Fig. 4.

Referring more particularly to the drawings, there is shown a frame, indicated generally at 10, formed of a strip of suitable magnetic material and having a generally L-shape, there being a horizontal or lower arm 11, as shown in the drawings, and an upright arm 12. The arm 11 of the frame 10 is provided with an enlarged portion 13, as best shown in Fig. 5, intermediate the ends thereof, which is provided with a central opening 14 defined in part by a flange 15 which is extruded. The extruded flange extends upwardly, as best shown in Fig. 3. There is an end portion 16 of said arm which has a downwardly projecting boss 17 which is also formed by extrusion and is adapted to be received in a recess or

2

opening 18 in a panel 19 to which the device is attached by means to be hereinafter described.

A core, indicated generally at 20, has a central portion 21 which is knurled, Fig. 3, and one end 5 of the core is reduced in diameter, as at 23, thereby forming a shoulder 24. The reduced end portion 23 is press-fitted into the opening 14 and the shoulder 24 abuts against the free end of the flange 15. It is to be noted that in knurling the portion 21, the pressure applied in the knurling process causes the metal of the portion 21 to be pressed longitudinally of the core at the shoulder 24 so as to form serrations. The teeth formed by the serrations will dig into the free end of the flange 15 and, thereby, hold the core 20 against rotation in the opening 14. Also, by providing the flange 15, there is a greater surface area for magnetic flux conduction between the frame and the core.

The coil 25 is mounted on the core 20, the knurled portion 21 of the core being received in a suitable axial opening in said coil. The axial coil opening is of such size as to snugly receive the knurled portion 21 so that the teeth of the latter portion will engage the coil and hold same against rotation. The coil 25 is held against longitudinal movement at one end by abutment against the arm 11 of the frame and is held against such movement at the other end by a washer 27 of insulating material which is received on the portion 21 and is engaged by a shoulder 28 at the outer side formed by an enlarged head 29 of the core at the end of said core opposite the arm 11 of the frame. The coil 25 is provided with a pair of contacts 31 and 32 to which wires 33 and 34 may be soldered, said wires comprising portions of a circuit which includes a source of electrical power such as a battery 35, the circuit includes a switch 36 which is manually operable although other means for operating said switch may be provided.

The arm 12 of the frame has a piece of insulating material, shown as a block 40, secured thereto by means of rivets 41 which also secure a contact 42 to said block. The contact 42 is centrally located on the front face of the insulating piece 40 and a suitable wire of an electric circuit may be soldered or otherwise suitably secured to said contact 42.

At one side of the contact 42 there is secured to the block 40 another contact, indicated generally at 44, and comprises a generally flattened part 45 secured to the block 40 by rivets 46 and having a forwardly extending part 47 to which an electric wire may be soldered or otherwise suit-

ably secured. At the opposite end of the flattened part 45, shown as the upper end, the contact extends upwardly at 48, as shown in Figs. 1, 3 and 4, and is provided with a laterally turned contact portion 49 which is shown as being generally horizontal in Figs. 1, 3 and 4 and is spaced upwardly of the upper edge of the block 40.

Adjacent the other side of the contact 42 but also spaced therefrom is a contact member indicated generally at 50 and includes a flattened portion 51 secured to the block 40 by rivets 52 and at the lower end of the flattened portion 51, as shown in the drawings, is a forwardly extending part 53 to which an electric wire may be secured by any suitable means such as soldering. At the other or upper end of the portion 51, is a contact end portion 55 which is generally horizontal and has a part which extends beneath the end portion 49 of the contact 44. The parts 49 and 55 extend generally parallel to each other and in spaced relationship and these parts are substantially round in cross section and may be of solid silver or other suitable silver alloy if desired. Inasmuch as this material has high thermo-conductivity, such heat as may be developed by the contact arc is conducted away very rapidly; however, other suitable contact metals and alloys may be used.

The contacts 42, 44 and 50 are part of the controlled circuits and the contacts 44 and 50 comprise the fixed contacts of said controlled circuits. There is a relay armature assembly, indicated generally at 60, which includes a lever 61 having a central part 62 of reduced width operably received in a notch 63 in the head 29 of the core 20. By notching the head 29 of the core, there is provided a pair of forked members 65 between which the lever 61 is mounted. The members 65 are provided with aligned openings which receive a pivot pin 66 secured in position by swedging at 67. Intermediate the ends of the lever 61, a transverse groove 68 is provided in the lever 61 and a corresponding groove 69 is provided in a retainer 70 which extends to the rear end of the lever 61 with a laterally turned portion 71 which extends over the rear edge of the lever 61 and holds the retainer against rotation on a rivet 72 provided to secure said retainer to said lever. The recesses 68 and 69 of the lever and retainer respectively, together form an opening in which the pivot pin 66 is operably received. Alternatively, a hole may be provided in the lever for reception of the pin 66 so that said lever will be rotatable on said pin as in the case of the arrangement which includes recesses formed in the lever and retainer 70. The opposite or forward end of the lever 61, as seen in the drawing, is provided with a contact 75 which is shown as a substantially round bar disposed between the portions 49 and 55 of the respective fixed contacts 44 and 50. The portions 49 and 55 of said fixed contacts are spaced apart a greater distance than the diameter of the contact 75 which is adapted to move between said fixed contacts with movements of the lever 61. The contact 75 is provided with a reduced end portion 76 received in a bore provided therefor in the adjacent end of the lever 61 and said contact 75 is held in position by swedging in the lever, as at 77. The armature assembly, comprising the lever 61, retainer and movable contact member 75, is substantially balanced with respect to the pivot 66. In other words, the part on one side of said pivot 66 substantially balances the part on the other side of said pivot.

The lever 61 is spring urged in the clockwise direction, as viewed in Figs. 1 and 3, so that the contact 75 normally contacts the contact portion 49 of the contact 44. The spring for urging the lever in the clockwise direction is shown as being a flat spring, indicated generally at 80, which is bent intermediate its ends to provide a substantially central contact point 81 which rests on or engages the bottom 82 of the notch 63 of the core 20 and the point of contact of the portion 81 with said bottom 82 is at all times forwardly or ahead of a vertical plane passing through the axis of the pivot pin 66 and the core 20, it being understood that the axis of the pin 66, as shown, intersects the axis of said core. More particularly, as shown in Figs. 1, 2 and 3, the point of contact of the portion 81 is leftwardly of the axis of said core. Adjacent the forward end of the spring 80, there is a small recess 84 pressed therein and adapted to receive the rounded tip of a conical end 85 of an adjusting screw 86 threaded into an opening provided therefor in the lever 61 adjacent the forward end thereof. Thus the rear portion of the spring 80 reacts between the point of contact of the portion 81 with the bottom 82 of the core notch and the adjacent end of rivet 72, the forward end of said spring reacts between said bottom 82 and the adjustment screw 86 urging the lever in the clockwise direction.

The rearward end of the spring is adapted to urge the rear end portion of the lever in the counterclockwise direction. As shown, the rear end portion of the spring 80 reacts against the rivet 72 although any other suitable contact with the rear portion of the lever will function satisfactorily. The arrangement thus described is such that the greatest force of the spring on the lever is such as to urge said lever in the clockwise direction so as to maintain the contact 75 in engagement with the contact 49 under normal conditions when the coil 25 is de-energized.

The connection between the adjustment screw 86 and the spring 80 is such that the spring is held in position in fixed relation to said screw thereby providing good maintenance of any adjustment setting. This arrangement also prevents movements of the spring forwardly, rearwardly, or sideways which would tend to change the spring tension on the lever and change the whole adjustment. Moreover, the three point contact of the spring tends to have a friction damping to the spring so that the effects of vibration are eliminated or substantially eliminated from the device.

The free end of the arm 12 of the frame 10 is spaced from the adjacent end of the lever 61, as best shown in Figs. 1, 3 and 4 and said free end of the arm 12 is so positioned that when the forward end of the lever 61 is moved in the counterclockwise direction so that the contact 75 engages the contact 55 said free end of arm 12 is still slightly spaced from the adjacent end of the lever.

The controlled circuits in the device are as follows: one wire of said circuits is connected to the contact 42 which is electrically, as well as physically, connected to the arm 12 of the frame and current flows through the frame, through the core 20, lever 61 and contact 75 to the contact 49, under normal conditions, and thence to the contact 47. When the coil 25 is energized and the contact 75 engages the part 55 of contact 50, the circuit then is through said contact 50 instead of through contact 44.

It is also to be noted that the magnetic circuit through the frame core and armature is complete

except for the gap between the forward end of the lever and the free end of the arm 12 of the frame which provides a highly effective and efficient magnetic circuit.

The device is readily attachable to panel 19, or any other suitable support, by means of a screw 90 which passes through a suitable opening provided in the panel 19 and is threadably received in a threaded bore 91 which extends axially or longitudinally in the adjacent end of the core 21. It is to be noted that inasmuch as the shoulder 24 of the core engages the adjacent or free end of the flange 15, the core cannot be pulled longitudinally in the opening 14 when the screw 90 is tightened so that the relay cannot be thrown out of adjustment even by excessive tightening of the screw 90.

I claim:

1. In an electric relay: a magnetic frame and core structure of generally U-shape; a coil for said structure; an armature pivoted to one arm of said structure and having a part extending into operable position with the other arm of said structure, said armature including a movable contact member; a pair of spaced rod-like contact members engageable by said movable contact member, said spaced contact members being substantially round in cross section; and yielding means urging the armature in a direction to effect engagement of one of said pair of contact members by said movable contact, the other said pair of contact members being engaged by the movable contact when said coil is energized and the armature is actuated as a result thereof.

2. In an electric relay: a frame and core structure of generally U-shape; a coil for said structure; a movable armature carrying a contact member which is round in cross section; a pair of fixed spaced contact members engageable by the first mentioned contact member, said pair of contact members being elongated and substantially round in cross section and comprising at least some silver; and yielding means urging the armature in one direction for engagement with one of the pair of contact members by the first mentioned contact, said armature being movable in the opposite direction upon energization of the coil so as to effect engagement of the first mentioned contact member with the other of said pair of contact members.

3. In an electric relay: a frame and core structure of generally U-shape; a coil for said structure; a movable armature carrying a contact member which is substantially round in cross section; a pair of elongated substantially parallel, fixed contact members in spaced relation to each other, said contact members being round in cross section and being adapted to be tangentially contacted by the first mentioned contact member; and yielding means urging the armature in one direction for engagement with one of the pair of contact members by the first mentioned contact, said armature being movable in the opposite direction upon energization of the coil so as to effect engagement of the first mentioned contact member with the other of said pair of contact members.

4. In an electrical relay: a generally U-shaped frame and core structure; a coil for said structure; and an armature pivoted to one arm of said structure and having a part extending to a position closely adjacent to but spaced from the other end of said structure, said armature having two positions and said structure and armature being of magnetic material and forming a sub-

stantially closed magnetic circuit; means wherein the free end of the armature carries a contact member movable with said armature and there are a pair of spaced contact members engageable by the movable contact member when the armature is in its respective positions and the frame structure and armature are in the electrical circuit of the mechanism as well as the magnetic circuit.

5. In an electric relay: a generally U-shaped frame and core structure, one arm of said structure having a notch therein; a coil for said structure; an armature having the intermediate portion received in said notch; means pivoting the central portion of said armature to the notched arm of said structure, said armature having a plurality of positions for controlling the relay circuits; and a leaf spring having a portion intermediate the ends thereof engageable with the bottom of the notch and having end portions engageable with the armature at opposite sides of the pivoting means for urging the armature toward one of said positions.

6. The invention defined by claim 5 wherein the spring is provided with an indentation adjacent one end thereof and there is an adjustment screw provided on the armature, said adjustment screw having a tapering end received in said indentation.

7. The invention defined by claim 5 wherein the point of contact of the portion of the spring engaging the bottom of the notch is at one side of a plane through the axis of the pivoting means for the armature and through the arm of said structure.

8. In an electric relay: a generally L-shaped frame having a hole therein partly defined by an upstanding flange extending axially of said hole; a core having an end portion press-fitted into the flanged hole; an electric coil mounted on said core; an armature pivotally mounted to the core and having a free end adjacent the end of one of the frame arms; a contact secured to said free end of the armature and movable therewith; a pair of fixed contact members alternately engageable by the movable contact member; and yielding means urging the armature in one direction.

9. In an electric relay: a generally L-shaped frame having a hole therein partly defined by a flange extending axially of said hole; a core having an end portion press-fitted into the flanged hole; a shoulder on said core adjacent the end received in the hole, said shoulder abutting against the free end of the flange about said hole; an electric coil mounted on said core; an armature pivotally mounted to the core and having a free end adjacent the end of one of the frame arms; a contact secured to said free end of the armature and movable therewith; a pair of fixed contact members alternately engageable by the movable contact member; and yielding means urging the armature in one direction.

10. In an electric relay: a generally L-shaped frame having a hole therein partly defined by a flange extending axially of said hole; a core having an end portion pre-fitted into the flanged hole, said core being provided with a knurled portion and a shoulder adjacent the end received in said hole in the frame, the teeth formed by knurling extending longitudinally beyond the shoulder which is engaged by the free end of the flange, portions of said teeth pressing into the adjacent end of said flange; an electric coil mounted on said core; an armature pivotally mounted to the core and having a free end adjacent the end of

one of the frame arms; a contact secured to said free end of the armature and movable therewith; a pair of fixed contact members alternately engageable by the movable contact member; and yielding means urging the armature in one direction.

11. In an electric relay: a generally L-shaped frame having a hole in one arm and partly defined by a flange extending axially of said hole and in the same general direction as the other arm of said frame; a boss on said one arm of the frame extending in the opposite direction from said flange for reception in a recess in a supporting member so that said frame may be held against displacement on the support; a core having an end portion press-fitted in the flanged hole, the end of said core received in said hole having a longitudinally extending threaded bore for reception of an attaching screw; an electric coil mounted on said core; an armature pivotally mounted to the core and having a free end adjacent the end of one of the frame arms; a contact secured to said free end of the armature and movable therewith; a pair of fixed contact members alternately engageable by the movable contact member; and yielding means urging the armature in one direction.

12. In a frame and core structure for an electrical device: a generally L-shaped frame member having a hole in one arm partly defined by a flange; and a core member having a shoulder adjacent one end thereof and an end portion extending outwardly of said shoulder and snugly received in said hole so that the free end of the flange is engaged by said shoulder, said end of the core having a threaded bore therein for reception of an attaching screw.

13. In an electric relay: a magnetic frame and core structure of generally U-shape; a coil for said structure; an armature pivoted to one arm of said structure and having a part extending into operable position with said other arm of said structure, said part including a movable contact member, there being another part extending in the opposite direction from the pivotal point of the armature adapted to balance the first mentioned part; a pair of spaced contact members engageable by said movable contact members; and yielding means urging the armature in a direction to effect engagement of one of said pair of contact members by said movable contact, the other said pair of contact members being engaged by the movable contact when said coil is energized and the armature is actuated as a result thereof.

14. In an electric relay: a frame and core structure of generally U-shape; a coil for said structure; a movable armature carrying a contact member which is substantially round in cross section; a pair of elongated substantially parallel, fixed contact members in spaced relation to each other, said contact members being round in cross section and being adapted to be tangentially contacted by the first mentioned contact member, said pair of contact members comprising at least some silver; a pair of fixed spaced contact members engageable by the first mentioned contact

5 member, said pair of contact members being elongated and round in cross section and comprising at least some silver; and yielding means urging the armature in one direction for engagement with one of the pair of contact members by the first mentioned contact, said armature being movable in the opposite direction upon energization of the coil so as to effect engagement of the first mentioned contact member with the other of said 10 pair of contact members.

15. In an electric relay: a generally L-shaped frame having a hole therein partly defined by a flange extending axially of said hole and outwardly of the plane of the adjacent surface of the frame; a core having an end portion press-fitted into the flanged hole; an electric coil mounted on said core; an armature pivotally mounted to the core and having a free end adjacent the end of one of the frame arms; a contact secured to said free end of the armature and movable therewith; a pair of fixed contact members alternately engageable by the movable contact member; and yielding means urging the armature in one direction.

16. In an electric relay: a generally L-shaped frame having a hole in one arm and partly defined by a flange extending axially of said hole and in the same general direction as the other arm of said frame; a core having an end portion press-fitted in the flanged hole, the end of said core received in said hole having a longitudinally extending threaded bore for reception of an attaching screw; an electric coil mounted on said core; an armature pivotally mounted to the core and having a free end adjacent the end of one of the frame arms; a contact secured to said free end of the armature and movable therewith; a pair of fixed contact members alternately engageable by the movable contact member; and yielding means urging the armature in one direction.

17. In a frame and core structure for an electrical device: a generally L-shaped frame member having a hole in one arm partly defined by a flange extending perpendicular to the surface of said one arm; and a core member having a shoulder adjacent one end thereof and an end portion extending outwardly of said shoulder and snugly received in said hole so that the free end of the flange is engaged by said shoulder, said end of the core having a threaded bore therein for reception of an attaching screw.
